UNITED STATES PATENT OFFICE.

EDWIN L. RELLER, OF ST. LOUIS, MISSOURI, ASSIGNOR TO THE DUCO ADDING MACHINE COMPANY, OF ST. LOUIS, MISSOURI, A CORPORATION OF MISSOURI.

ACCUMULATOR FOR CALCULATING-MACHINES.

1,095,674.

Specification of Letters Patent.

Patented May 5, 1914.

Application filed October 16, 1911. Serial No. 654,982.

To all whom it may concern:

Be it known that I, EDWIN L. RELLER, a citizen of the United States, residing at the city of St. Louis, State of Missouri, have invented certain new and useful Improvements in Accumulators for Calculating-Machines, of which the following is a specification, reference being had therein to the accompanying drawings.

10 The present invention relates to improvements in calculating machines and is more especially applicable to calculating machines of the type embodied in the pending application of Edwin A. Reed, Edwin L. Reller, 15 William L. Swift, and Albert J. Meier, filed April 3, 1911, Serial No. 618,655, the present improvements being directed particularly to the accumulator for machines of the type therein disclosed.

20 An object of this invention is to provide an accumulator whereby the printing wheels thereof are automatically set to print ciphers in all columns to the right of the column containing the selected numeral.

25 Further objects of this invention are to provide an accumulator embodying simple and efficient mechanism for clearing the same after each total printing operation, improved carry-over mechanism for the 30 printing wheels, an automatic signal or alarm operative to indicate when a carry-over has occurred when the accumulator has been set to simultaneously add two or more columns, and to provide a generally improved 35 accumulator, all as will be hereinafter described, the features of novelty being set forth particularly in the claims.

In the accompanying drawings, wherein similar parts are designated by the same 40 reference characters, Figure 1 is a top plan view of an accumulator embodying the present invention; Fig. 2 represents an enlarged detail sectional view taken axially through the set of printing wheels on the line 2—2 of Fig. 1 and showing the clearing devices associated therewith; Fig. 3 is an exterior side elevation of one side of the accumulator; Fig. 4 represents a section on the line 4—4 of Fig. 1 and looking in the direction of the 45 arrows; Fig. 5 represents a vertical section taken centrally through the accumulator, indicating the manner in which the accumula- 50 tor actuating bars coöperate therewith; Fig. 6 represents a section on the line 6—6 of Fig. 5 and looking in the direction of the 55 arrows; Fig. 7 is a diagrammatic view showing the normal relation between a printing wheel of the accumulator and its respective actuating bar; Fig. 8 is a sectional view showing a portion of the clearing mechanism; Figs. 9 and 10 are detail views showing the operative connections between the accumulator and the main actuating bar of the machine; Fig. 11 represents a section on the line 11—11, Fig. 1 and looking in the 65 direction of the arrows; Fig. 12 is an elevation on an enlarged scale of the resetting means for the carry-over pawls, as viewed from the right in Fig. 5; Fig. 13 is a detail perspective view of the comb for guiding 70 the actuating bars in the accumulator, and Fig. 14 is a similar view of a guiding comb used in the accumulator.

The present embodiment of this invention is, as previously stated, applicable particularly to calculating machines of the type disclosed in the above-identified application, and in the drawings illustrating such embodiment, the main operating elements are represented as constituted by a series of bars 80 5 which are themselves actuated from the item-printing mechanism, (not shown), so as to transmit their movements to the total-printing wheels 54. There is one of these bars 5 for each printing wheel 54, and at the 85 left-hand side of each bar is mounted a shiftable plate 13, the movement of the said plates being largely concerned, however, with the item-printing mechanism, which forms no part of the present invention. Accordingingly, the operation of the plates with 90 respect to that mechanism requires no description, beyond the fact that the plates are guided relatively to their respective bars by means of pins 26 which are located at the 95 forward ends of said plates and work freely in longitudinal slots 27 in said bars. The upper, forward edge of each bar 5 is formed with a rack 28, to coöperate with the corresponding printing wheel 54, as subsequently described, and the lower forward edge of each plate is provided with a forwardly-directed hook 29, the latter being utilized to engage and elevate a cross-bar 32 100

when the plate is moved forwardly. This cross-bar connects a pair of arms 31 which are borne by a suitably-mounted transverse shaft and are formed at their free front ends with upwardly-directed hooks 30 for a purpose to be hereinafter described, the hooks being normally held in lowered position by a spring or springs 34.

The forward ends of the rack bars 5 and 10 the coöperative plates 13 normally rest upon a supporting cross member 35 Figs. 5 and 13 which is arranged at the entrance to the accumulator and has a comb 36 through which the rack bars and plates operate, 15 whereby such parts are maintained in proper spaced relation. A jack 37 is located immediately adjacent to the support 35, the jack embodying a pair of end members 38, which are connected by and rigidly 20 mounted on a cross bar 39. Vertical movement, and a limited extent of forward and backward movement are permitted the upper portion of the jack by the links 40, which are pivotally connected to the main 25 side plates 41 of the accumulator frame or casing at the points 42, the opposite ends of these links being slotted and connected to the jack by the pins 43. The cross bar 39 is secured to a pair of arms 44, Fig. 3, 30 each of these arms being pivotally connected at 45 to the main side plates. The end members of the jack have extensions 46 adapted to bear upon the laterally turned 35 upper ends 47 of a pair of supporting detents 48, these detents being pivoted at 49 to the main side plates 41 and being yieldably held in position to retain the jack elevated by springs 50, one end of each of 40 these springs being attached to an eccentrically arranged eye 51 on the respective detent while the opposite end of the spring is attached to the jack, whereby the jack will be pulled down after being released by the 45 detents. The detents are disengaged from the jack when the upper portion of the latter is rocked toward the right in Fig. 5, the disengagement being effected by the prolongation 52, which bears against and rocks the respective detent. The upwardly 50 directed hooks 33, however, when elevated, engage the upper part of the jack and thereby lock the latter in elevated position.

The toothed actuating wheel 53 for each printing wheel 54 is located directly above, 55 but in normally disengaged relation to the rack teeth 28 of the respective rack bar. The printing wheels and their actuating wheels correspond in number to the rack bars, these wheels being mounted to revolve 60 on a common shaft 55, and the periphery of each printing wheel carries a circular row of type faces 56 bearing consecutively arranged numerals, and, also, a type face 57 bearing a zero character. Cams 58 are, 65 also, interposed between the printing

wheels, each cam having a projection 59 adapted to coöperate with a projection 60 formed on the forward end of a corresponding carry-over pawl 61, the latter being fulcrumed on a cross bar 62, which extends 70 through a cam slot 63 in the pawl. The several carry-over pawls for the different printing wheels are maintained in proper spaced relation by a transverse comb 64, and each pawl is returned to and held in 75 normal position by a tension spring 65. A pawl 53^a is rotatably mounted on cross rod 53^b and is held in engagement with the toothed wheel 53 by the spring 65, so as to prevent same from spinning. The nose of 80 pawl 53^a normally occupies a position between two teeth of the wheel 53, in order to allow same to be rotated rearwardly to set the zero type face of its printing wheel 54 in printing position in the manner hereinafter described. The shaft 55 bearing the 85 printing wheels is formed with a longitudinal slot, and a clearing comb 66 Fig. 2 operates radially of the axis of the shaft and within this slot, the projections or teeth of 90 the comb being adapted to coöperate with the projections 67 on the edges of the cams 58 for the purpose of restoring all the printing wheels to initial position after each total has been printed. The comb is controlled by a pair of arms 68 which are pivoted on the main side plates and are operatively connected by the links 69 to a pair of crank arms 70, the latter being attached to the shaft 71. Members 71^a fixed to shaft 71 100 prevent the detents 48 from being moved out of supporting engagement with extensions 46 of the end members 38 of jack 37, when said shaft is rotated by the depression of the clearing key (not shown), with which 105 same is operatively connected.

One end of the printing wheel shaft 55 has a pinion 72 Fig. 4 fixed thereon, the pinion in the present instance having a stop-tooth 73, and this pinion coöperates with a 110 toothed sector 74, having a stop tooth 75 adapted to coöperate with that of the pinion after the latter has completed substantially nine-tenths of a revolution. The sector 74 is fixed to a shaft 76, and it, also, has an extension below such shaft, which is pivotally connected to a link 77, the latter having a hook-shaped and downwardly turned end 78 arranged to coöperate with a pin 79 borne by a lever 80. The latter is mounted 120 to rock on the transverse shaft 45 and is operatively connected to a resetting frame 81, Fig. 5, a tension spring 82 serving to return and retain such parts in normal position. The upper edge of the lever 80 is 125 formed with a cam surface 83 Fig. 4 to coöperate with the arm 84 of a bell-crank lever which is mounted on a shaft 85 and has an arm 86 which bears a cross bar 87, a similar arm 88 Fig. 3 being provided at the op- 130

posite side and connecting the shaft 85 and the cross bar 87.

The shaft 76 for the clearing mechanism is operated by a crank 88^a, Fig. 8, fixed thereto, said crank being pivotally connected to one end of a hook 89 that is formed with an upwardly opening recess 90 adapted to receive a pin 91 carried by a reciprocatory bar 25, which is operated from the handle (not shown) of the machine. Hook 89 is elevated to engage the pin 91 in said recess by a vertically movable link 92, which has a horizontal slot 93 operatively associated with a pin 94 fixed to the hook 89, the link 92 being elevated to set the clearing mechanism into operation by an arm 95 fixed to the shaft 71, the latter being controlled or operated by the clearing key.

The reciprocatory bar 25 is, also, operatively connected by a pin 96 thereon, to a crank plate 97, the bar being guided for rectilinear movement by the pin 98, Fig. 9, which co-operates with a longitudinal slot 99 in the bar, and the pin 96 operates in a radial slot 100 in the crank plate 97, the latter being mounted loosely on a shaft 101 and being turnable about the latter as a center. The upper edge of the crank plate 97 has a concentric portion 102 Fig. 8 and, also, a notch 103, the latter being adapted to receive a laterally turned projection 104 formed on a second plate 105. The plate 105 has a central slot 106 which accommodates the shaft 101 and permits the plate 105 to shift transversely thereof, the plate 105 also bearing a pin 107 which operates in a radial slot 108 formed in a plate 109, the latter plate being fixed to turn with the shaft 101. The plate 105 is turnable with the plate 109 and is shiftable to control the operative relation between the latter and the crank plate 101, the projection 104 on the latter being normally held in the notch 103 by a tension spring 110.

The shaft 101 also has a cam 111 Fig. 4 fixed thereon, this cam having the successively arranged stepped surfaces 112, 113 and 114. The cam also carries a pawl 115 which is pivoted thereon by the pin 116 and has a tension spring 117 attached thereto which operates to normally hold the pawl in a predetermined position. The pawl also has a nose 118, and a shoulder 119 which co-operates with a pin 120 on the cam for the purpose of preventing movement of the pawl beyond a predetermined point in one direction. One of the arms 44 of the jack is part of a bell crank, the other arm 121 of which has a nose 122 arranged to co-operate with the cam 111. The arm 86 also has an inclined projection 123 arranged in co-operative relation to the nose 118 of the pawl 115, this arm being normally held in inactive position by the tension spring 124. The shaft 101 also has a gear sector 125 Fig. 11

fixed thereon, a portion of the periphery of this sector bearing the teeth 126 while the remainder of its periphery is smooth. The teeth of this sector co-operate with a mutilated pinion 127 mounted on a stud 128, a portion of the periphery of this pinion being interrupted to form a stop shoulder 129 which is adapted to co-operate with the smooth or interrupted portion of the co-operating sector.

A second pinion 130 and also a cam 131 are mounted to turn with the pinion 127, the pinion 130 co-operating with an idler 132 which in turn co-operates with a pinion 133, the latter being mounted loosely on a shaft 134 and being turnable with an arm 135 on said shaft. Such arm carries a pawl 136 which co-operates with a one tooth ratchet wheel 137 fixed to the shaft 134, the pawl being pressed into engagement with its co-operating ratchet wheel by the spring 138. Displacement of the pawl relatively to the ratchet wheel is prevented by the laterally turned projection 139 on the arm 135 which is located at the outer side of the pawl. A locking disk 140 is also fixed to turn with the shaft 134, and serves to insure one complete revolution of such shaft at each actuation, the periphery of the disk having a pair of opposed shoulders 141 and 142, the former adapted to abut against a dog 143 to prevent retrograde motion of the ratchet wheel 137 and the shaft 134, and the shoulder 142 being controllable by the dog 144. The dogs 143 and 144 are pivotally mounted on a common shaft or pin 145 and have extended arms which are connected by a tension spring 146 which tends to move and hold the dogs in engagement with the disk 140, the dog 144 also having an arm 147 which bears upon the cam 131 in such a way that when the parts are in initial position, the cam will hold the dog 144 in inactive position and will permit forward rotation of the shaft 134, and after this shaft has been partially rotated, the cam will permit the dog 144 to move into engagement with the periphery of the disk 140 and when such disk and consequently the shaft 134, have completed one full revolution, the dog 144 will engage the shoulder 142 of the disk and thereby prevent further rotation of the disk in a forward direction. The dog 143 also co-operates, at this time, with the shoulder 141 to prevent retrograde motion of the shaft. While the shaft 134 is thus locked from rotation in either direction the sector 125 returns to initial position, the pawl 136 moving about the periphery of the ratchet wheel 137 and reengaging behind the tooth thereof preparatory to the next succeeding operation. A multiple cam is fixed to the shaft 134, one of the cam elements 145^a Fig. 5 thereof being provided for each of the printing wheels and associated parts, excepting the printing 130

wheel at the extreme right, and these elements are spaced at equal angles about the shaft and progressively from right to left. A set of levers 146^a are mounted to operate independently on a cross shaft 147^a, one of these levers being provided for each cam element, and each lever bears a roller or projection 148 to coöperate with its respective cam element, the upper end 149 of each of these levers being utilized for a purpose to be hereinafter described. A disk 150 Fig. 4 is, also, fixed on the shaft 134, it having a wedge-shaped notch to receive a correspondingly shaped projection on one arm of a bell crank 151, the latter being pivoted at 152 and having a tension spring 153 attached to its other arm, the spring acting to force the projection on the bell crank into the wedge-shaped notch in the disk and thereby automatically position the shaft 134 in initial position. The accumulator, also, embodies a set of members 154 Fig. 5, which are operative in a manner to be hereinafter described, to automatically set the printing wheels of the accumulator in cipher-printing position, there being one of these members for each printing wheel. One end of each of these members has a longitudinal slot 155 to receive the cross member 156 while the opposite end thereof is formed with an upwardly directed projection 157 which is adapted to enter a wedge-shaped notch 158 formed in the periphery of the respective printing wheel. Each of the members is provided at an intermediate point with a locking shoulder 159 and, also, with an angular slot 160, the latter receiving a pin 161 borne by the arm 162 of a bell crank, such arm having a depending projection 163, which coöperates with a comb 164, whereby such parts are maintained in proper spaced relation.

A tension spring 165 normally acts to pull the member 154 to the right in Fig. 5, and the other arm 166 of the bell crank, which is pivoted on the cross rod 156 is engaged by a tension spring 167, which normally tends to lift the arm 162. Each member 154 is formed with a shoulder 168, which is adapted to be engaged by the upper transverse member of the cradle 81, whereby, when the cradle is rocked toward the left in Fig. 5, all of the released members will be restored to normal or initial position. A latch 169 is provided for each member 154, and these latches are pivotally mounted at their forward ends on the cross shaft 85 and are formed with shoulders 171 arranged to co-operate with the shoulders 159 of the respective members, when the latches are lowered, thereby preventing forward movement of such members under the action of their springs 165. The forward end of each latch is provided with a laterally turned projection 172 which is adapted to bear upon the

top of each plate 13, the latter when lowered and resting upon the support 35 permitting the latch 169 to remain in locked engagement with its respective member 154. When such plate is elevated in a manner to be hereinafter described, the latch will be elevated and in consequence disengaged from its respective member 154, thereby permitting the latter to move forwardly under the influence of its spring 165, the projection 157 on such member then acting to turn the respective printing wheel sufficiently to bring the zero type face 57 thereon, into printing position. Continued movement of the member 154 causes its projection to disengage 80 from the printing wheel. The latches 169 are held in locking position by springs 1169 and these springs also act to hold the levers 146^a in coöperative relation with the respective cam elements 145^a.

Each carry-over pawl 61 is provided toward its rear end with a horizontal projection 170 and also with a downwardly-directed projection 173, the latter, when the corresponding end of the pawl is lowered, 85 being in the path of the end 149 on its respective lever 146^a. A set of locking dogs 174, one for each carry-over pawl, is mounted to reciprocate longitudinally in guides 175 in the upper portion of the accumulator frame, each of these dogs having a depending projection formed with a notch 176, which, when the adjacent end of the corresponding carry-over pawl is lowered, receives the horizontal projection 170 thereon, 90 and thereby holds such end of the pawl in lowered position. A projection 61^a on the upper edge of pawl 61 normally engages the forward guide 175 and thereby prevents said pawl from being moved to rotate its type wheel 54, until the rear end of same is lowered sufficiently to allow the projection 170 to enter notch 176. A tension spring 177 operates to move these dogs to the left, Fig. 5, and each dog is formed with an upwardly 95 projecting arm 178 bearing a latch 179, which is pivoted thereon. Each latch has a shoulder 180 adapted to snap over and lock itself to the cross member 181 of a rocking frame 182 Fig. 4, the arms thereof being 100 pivoted at 183, and a pair of springs 184 operate to move such frame to the left in Fig. 4. A controlling device 185 is provided for each latch, each of these devices having a laterally turned projection 186, which is located beneath its respective latch, and when any one of the controlling devices is actuated to lower its projection 186, the corresponding latch will be permitted to descend 105 and allow its shoulder 180 to engage the cross member 181 of the rocking frame. A spring 187 Fig. 5 is provided to yieldably hold the controlling device in operative and inoperative positions. Ordinarily, however, all the controlling devices will be set in inoper- 110

ative condition so that the latches will be supported thereby, and will not engage the cross member of the rocking frame 182, certain of these latches being released when the machine is being operated to simultaneously add a plurality of sets or columns of numerals. A spring 188 acts upon each latch to depress it, and each latch has a tail 189 which, when the respective dog 174 moves forwardly, cooperates with the under side of the cross member 190, such latches as have been depressed being thereby raised to release the rocking frame. This rocking frame 182 forms part of a signal for indicating when a carry-over has occurred, it having a spring supported clapper 191 Fig. 3 fixed thereto, and when the rocking frame is released by the disengagement of the latch or latches, it suddenly returns to initial position under the influence of its springs 184, the clapper striking and sounding the bell 192. To facilitate cleaning, adjustment or repair of the accumulator, the shaft 134 and the parts thereon, are preferably mounted in a pair of auxiliary plates 193 which are detachably secured to the main side plates.

The operation of the mechanism, is briefly, as follows:—The entering of the items is accomplished in the same manner as described in the aforesaid application, that is to say, by depressing and rotating the finger-pieces or sectors, and when each finger piece or sector is depressed or rotated, the rack bar 5 which is operatively connected thereto, moves forwardly and into the accumulator carrying the corresponding plate 13 with it, it being understood that the rack teeth 28 of the bar do not engage the respective toothed actuating wheel when the rack bar so enters the accumulator. The forward movement of a rack bar into the accumulator causes its forward end to engage the jack 37, and to rock the jack toward the right in Fig. 5 so as to trip or release it from the detents or triggers which hold it in elevated position, with the result that the jack drops and thereby rotates the bell crank arm 121 to the left in Fig. 4, causing the nose 122 thereon to bear against the surface 112 of the cam 111.

After the finger pieces or sectors have been set according to the item to be printed, the machine is operated, causing forward movement of the operating bar 25, which latter in turn causes the impression mechanism to operate and print the item. The forward movement of the bar 25 also causes the crank plate 97 to rotate counter-clockwise, Fig. 8, and this crank plate operates through the medium of the plate 105 and its projection 104, and the plate 109 to rotate the main accumulator shaft 101 in a counter-clockwise direction, thereby causing the cam surface 112 of the cam 111 to press against the nose 122 of the bell crank arm 121. Rotation of

said cam will rock the bell crank clockwise until the nose 122 thereon reaches the part 113 of the cam, with the result that the bell crank is, thereby, caused to raise the jack 37, and the jack in turn operates to raise the adjacent ends of the rack bars 5 and the associated plates 13. These rack bars, however are not at this time raised sufficiently to cause their rack teeth 28 to engage the toothed actuating wheels 53, although the plates 13 are at this time raised sufficiently to lift their respective latches 169 which then release or unlock their corresponding members 154, permitting the latter to be pulled to the right in Fig. 5 by 80 their respective springs. Such movement of each member 154 causes such member to operate upon and turn its respective accumulator or printing wheel so as to bring its zero type face 57 into printing position, 85 further movement of such member causing its projection 157 to be pulled out of engagement with the notch 158 in the accumulator wheel, and this projection is held out of the path of the accumulator wheel until 90 the clearing operation takes place. As these members normally hold the respective accumulators in such position that the zero type faces thereon are not in printing position, the printing of a total will not 95 cause ciphers to be printed to the left of the left-hand digit of the total, as each accumulator wheel to the left of the left-hand digit remains in normal position. Lifting of the rack bars and their associated 100 plates 13 causes the hooks 29 on said plates to lift the arms 31 carrying the hooks 33, the latter being thereby caused to engage the rear side of the jack and the jack then acts as a lock to prevent such finger pieces 105 as have not been actuated, from being actuated until all the actuated or depressed finger pieces have been restored to initial position. After the accumulator wheels have been rotated to present their zero type 110 faces to the printing position, the further rotation of the cam 111 carries the cam surface 114 into engagement with the nose 122, thereby rocking the bell crank farther in a clockwise direction and causing it to lift 115 the jack higher until it reaches its initial position, the rack bars being then elevated sufficiently to engage the rack teeth 28 thereon with the respective actuating wheels 53, and hence when the rack bars and their associated plates are restored to initial position, the accumulator wheels will be rotated 120 in a clockwise direction, Fig. 5.

The carry-overs are produced in the following way: When an accumulator wheel 54 125 has been rotated to such extent as to cause the type face thereon bearing the numeral "9" to pass the printing position, the projection 59 on the cam 58 strikes the projection 60 on the carry-over pawl 61 for the 130

next accumulator wheel to the left, thereby tilting the pawl about its fulcrum 62 and causing its opposite end to be lowered, and when the projection 170 on this end of the 5 pawl alines with the notch 176 in the corresponding dog 174, the latter moves to the left, Fig. 5, and thereby engages such projection in its notch, the corresponding end of the carry-over pawl being thus held in 10 depressed position and with its downturned projection 173 in the path of movement of the upper end 149 of the corresponding restoring lever 146^a. Hence when such lever is 15 rocked toward the right, Fig. 5, by rotation of its respective cam element 145^a, the carry-over pawl will be pulled toward the right, thereby producing the carry-over. The cam elements 145^a which actuate the restoring levers are so adjusted that each revolution 20 of the shaft 134 supporting them will cause the carry-over to take place in succession and from right to left. The shaft 134 which carries the multiple restoring cam receives one complete revolution at each operation 25 from the sector 125 which is fixed to turn with the shaft 101 and through the medium of the gears and controlling devices hereinbefore described.

After the shaft 134 has been rotated once 30 through a complete revolution, the trigger or pawl 115 pivotally mounted on the cam 111 engages the inclined surface of the projection 123 on the arm 86, causing movement of the latter toward the right, Fig. 4, and 35 carrying the cross rod 87 into position to reset the dogs 174, whereby the carry-over pawls are released and permitted to return to initial position under the influence of springs 65. After this has been accomplished, continued rotation of the cam 111 40 will carry the pawl 115 past the projection 123, allowing the bell crank arm 86 and its cross bar 87 to return to normal position. Reverse motion of the operating bar 25 toward 45 initial position returns the cam 111, and the mechanism for turning the shaft 134 to normal position.

Clearing of the accumulator is effected as usual by operating a suitable clearing key, 50 such key causing rotation of the shaft 71 so as to set the clearing comb 66 in operative condition, and also elevating the hook 89 to cause the recess 90 therein to receive the pin 91 on the operating bar 25 and during the 55 forward movement of the bar 25, the shaft 76 is rotated, whereby the shaft 55 is rotated through substantially nine-tenths of a revolution, the comb 66 cooperating with the projections 67 to return the accumulator 60 wheels to initial position with their zero type faces at the printing position, after which the bar 25 returns to initial position and restoring the comb 66 to its original position. During the forward movement of the operating bar 25, the link 77 which is pivotally 65

connected to the gear segment 74 moves toward the right, Fig. 4, until its end 78 hooks over the pin 79 on the plate 80, and when the bar 25 returns to initial position, the cradle 81 is rocked to restore the members 154 70 to initial position with their projections 157 engaged in the notches 158 of the respective accumulator wheels and as these members are restored, the accumulator wheels will also be returned to their initial positions. 75 The plate 80 acting on the arm 84, also tilts the arm 86 toward the right, Fig. 4, thus insuring the resetting of the locking dogs 174 and the proper return of all the carry-over pawls to normal position. Elevating of the 80 link 92, which serves to raise the hook 89, also serves to lift the plate 105, thereby disengaging the projection 104 from the notch in plate 97 and allowing the latter to rotate fully on its shaft 101. 85

Should an accumulator wheel which has not been rotated out of its initial position by its member 154, be rotated by its carry-over pawl, the projection 157 of the member 154 is forced out of the notch 158 in the wheel and the said member is thereby lowered and released from its latch 169, the member 154 being then pulled toward the right, Fig. 5, by its spring. The spring attached to the arm 166 tends to raise the pin 95 161 whereby the projection 157 is normally held in engagement with the notch 158 in its corresponding accumulator wheel.

What is claimed is:—

1. In an accumulator, the combination of 100 a set of accumulator wheels, a set of carry-over pawls each capable of tilting and longitudinal movements, a dog for holding each pawl in tilted position an actuating lever arranged to operate upon the respective pawl while in tilted position, and a cam for operating said lever.

2. In an accumulator, the combination of 110 a set of accumulator wheels, a set of carry-over pawls each capable of tilting and longitudinal movements, a reciprocatory dog for locking the pawl in tilted position, means for reciprocating the pawl while in tilted position, and means for subsequently disengaging the dog from the pawl.

3. In an accumulator, the combination of 115 a set of accumulator wheels, a set of carry-over pawls each capable of reciprocatory movement, a reciprocatory dog coöperative with each pawl, a latch carried by each dog, and a signal operative by said latch.

4. In an accumulator, the combination of 120 a set of accumulator wheels, a set of carry-over pawls each movable longitudinally, a longitudinally movable dog coöperative with each pawl, a pivoted latch carried by each dog, a cross bar adapted to be engaged by said latches, and a signal operative by said cross bar.

5. In an accumulator, the combination of 125 130

- a set of accumulator wheels, a set of carry-over pawls each movable longitudinally, a longitudinally movable dog coöperative with each pawl, a pivoted latch carried by 5 each dog, a cross bar adapted to be engaged by said latches, a signal operative by said cross bar, and devices individual to said latches for holding them in disengaged relation to said cross bar.
- 10 6. In an accumulator, the combination of a set of accumulator wheels, a set of carry-over pawls each movable longitudinally, a longitudinally movable dog coöperative with 15 said pawl, for holding the latter in set position, means for reciprocating the pawl to effect the carry-over, and means for restoring said dogs.
7. In an accumulator, the combination of a set of accumulator wheels, a set of carry-over pawls each movable longitudinally, a longitudinally movable dog coöperative with 20 said pawl, for holding the latter in set position, means for reciprocating the pawl to effect the carry-over, a bell crank having 25 a cross member coöperative with said dogs, a rotatable member, and a trigger carried by said rotatable member and operative on said bell crank to reset said dogs.
8. In an accumulator, resetting mechanism 30 for the carry-over pawls embodying a shaft, means thereon operative successively upon said carry-over pawls, a reciprocatory gear segment, a ratchet interposed between said segment and shaft for rotating the latter, a locking disk fast on said shaft, and means arranged to engage said disk when 35 said shaft has completed one full revolution, to arrest its rotation.
9. In an accumulator, resetting mechanism 40 for the carry-over pawls embodying a shaft, means thereon operative successively upon said carry-over pawls, a reciprocatory gear segment, a ratchet interposed between said segment and shaft for rotating the latter, a locking disk fast on said shaft and 45 provided with a pair of spaced teeth, a pawl arranged to engage one of said teeth when said shaft has completed one full revolution, to arrest its rotation, and a second pawl 50 arranged to simultaneously engage the other tooth to prevent retrograde motion of said shaft.
10. In an accumulator, resetting mechanism 55 for the carry-over pawls embodying a shaft, a multiple cam thereon having elements corresponding in number to the carry-over pawls and operatively connected thereto, a reciprocatory gear segment, a ratchet between said segment and shaft for rotating 60 the latter, means for automatically arresting rotation of said shaft after it has completed one revolution, and means for preventing retrograde motion of the shaft after such revolution has been completed.
- 65 11. In an accumulator, resetting mechanism 65 for the carry-over pawls embodying a shaft, a multiple cam thereon having elements corresponding in number to the carry-over pawls and operatively connected thereto, a reciprocatory gear segment, means between the segment and shaft for rotating the latter, a cam operative by said segment, and a pawl controlled by said cam for automatically arresting rotation of said shaft.
12. In an accumulator, resetting mechanism 70 for the carry-over pawls embodying a shaft, a multiple cam thereon having elements corresponding in number to the carry-over pawls and operatively connected thereto, a reciprocatory gear segment, means operative by said segment for rotating said shaft, means for automatically arresting rotation of such shaft, and a device for normally holding the shaft in initial position.
13. In an accumulator, resetting mechanism 75 for the carry-over pawls embodying a shaft, a multiple cam thereon having elements corresponding in number to the carry-over pawls and operatively connected thereto, a reciprocatory gear segment, means operative by said segment for rotating said shaft, means for automatically arresting rotation of such shaft, means for preventing retrograde movement of the shaft, and means for yieldably holding the shaft in 80 normal position.
14. In an accumulator, the combination of a set of accumulator wheels, a clearing comb therefor, a reciprocatory operating bar, means controlled thereby for setting said comb in clearing condition, means for rotating the wheels to restore the same to initial position, and a hook having means for setting it to form an operative connection between said bar and the means for rotating 85 the accumulator wheels.
15. In an accumulator, the combination of 90 accumulator wheels, clearing mechanism therefor, a hook for operating said clearing mechanism, carry-over mechanism for said wheels, means for actuating the carry-over mechanism embodying a shaft, a plate capable of being coupled and uncoupled with respect thereto, an operating bar connected to said plate, and a link for operatively connecting said hook to the operating bar and for uncoupling said bar with respect to 95 said plate.
16. In an accumulator, the combination of 100 accumulator wheels, clearing mechanism therefor, a hook for operating said clearing mechanism, carry-over mechanism for said wheels, means for actuating the carry-over mechanism embodying a shaft, a plate fixed to said shaft, a shiftable plate connected to 105 turn with the plate first mentioned, a crank plate loosely mounted on said shaft and having a notch to receive the projection on the shiftable plate, an operating bar connected to said crank plate, and a link adjustable to 110
- 115
- 120
- 125
- 130

connect said hook to the operating bar and to adjust the shiftable plate to disconnect it from said crank plate.

17. In an accumulator, the combination of 5 accumulator wheels, clearing mechanism therefor, a hook for operating said clearing mechanism, carry-over mechanism for said wheels, means for actuating the carry-over mechanism embodying a shaft, restoring 10 means for the carry-over mechanism, a pivoted lever coöperative with said restoring means, and bearing a pin, and a hook operatively connected to the clearing mechanism and arranged to engage and act upon the pin 15 of said lever thereby to actuate the restoring means.

18. In an accumulator, the combination of 20 accumulator wheels, clearing mechanism therefor embodying a pivoted segment, carry-over mechanism for said wheels, restoring means for the carry-over mechanism 25 embodying a bell crank, a pivoted lever having a cam surface bearing against said bell crank and bearing a pin, and a hook pivotally connected to said segment and operative upon the pin of said lever.

19. In an accumulator, the combination of 30 accumulator wheels, clearing mechanism therefor, embodying a pivoted segment, carry-over mechanism for said wheels, restoring means for the carry-over mechanism 35 embodying a bell crank, a pivoted lever having a cam surface bearing against said bell crank and bearing a pin, and a hook pivotally connected to said segment and operative upon the pin of said lever, devices 40 for setting said wheels in cipher printing position, and a cradle actuated by said pivoted lever for restoring said devices to initial position.

20. In an accumulator, the combination of accumulating wheels, reciprocatory bars for actuating them, a jack for moving said bars into operative relation to said wheels, 45 means releasable by the jack for supporting the latter in elevated position, an operating bar, a rotatable cam operative thereby, and a lever coöperative with said cam and operative to restore the jack to elevated position.

21. In an accumulator, the combination of 50 a set of accumulator wheels, reciprocatory actuating bars therefor, a pivotally mounted and vertically movable jack for controlling the operative relation between said bars and their respective wheels, triggers for holding the jacks in elevated position, a rotatable cam, and means operative by the cam for elevating the jack after it has been released 60 from said triggers by said bars.

22. In an accumulator, the combination of 65 a set of accumulator wheels, a set of carry-over pawls each capable of reciprocatory movement, means for holding each pawl in released position, means operative

upon each released pawl to shift it endwise in one direction for effecting the carry-over between the wheels, and means for subsequently shifting the released pawl endwise in the opposite direction to return it 70 to normal position.

23. In an accumulator, the combination of 75 a set of accumulator wheels, a set of carry-over pawls each capable of tilting and longitudinal movements, means for tilting each pawl, a dog for holding each pawl in tilted position, and a device operative upon the tilted pawl to reciprocate it longitudinally for effecting the carry-over between the wheels.

24. In an accumulator, the combination of 80 a set of accumulator wheels, a set of longitudinally movable carry-over pawls each provided with a projection, and a set of dogs each provided with a projection adapted to engage the projection on the corresponding pawl for holding the latter in released position, and means operative upon each released pawl to move the same endwise in one direction to effect the carry-over between the wheels.

25. In an accumulator, the combination of 85 a set of accumulator wheels, a set of longitudinally movable carry-over pawls each capable of tiltable and longitudinal movements, each pawl having a pair of projections upon one end thereof, means for tilting each pawl, a locking member adapted to engage one of the projections on each tilted pawl, and a member adapted to engage the 90 other projection on the tilted pawl to move the latter endwise in one direction, to effect the carry-over between the wheels.

26. In a calculating machine, the combination of a set of accumulator wheels, a 105 clearing comb operative to restore each wheel to cipher printing position, and means for subsequently restoring each wheel to non-printing position.

27. In a calculating mechanism, the combination of a set of accumulator wheels, clearing mechanism therefor, means for operating the clearing mechanism embodying 110 a rock shaft, a lever operative from said shaft, and means operative by said lever 115 for restoring the wheels to normal position.

28. In a calculating mechanism, the combination of a set of accumulator wheels, clearing mechanism therefor, means for operating the clearing mechanism embodying 120 a rock shaft, a lever operative from said shaft, a cradle operatively connected to said lever, and means operative by said cradle for restoring the wheels to normal position.

29. In a calculating mechanism, the combination of a set of accumulator wheels, clearing mechanism therefor, means for operating the clearing mechanism embodying 125 a rock shaft, means for rocking said shaft, a member borne by said shaft, means opera- 130

tive by said member for restoring the
wheels to cipher-printing position, and
means operative by said member for restor-
ing the wheels to non-printing position
5 after same have been restored to cipher-
printing position.

In testimony whereof I hereunto affix my
signature in the presence of two witnesses.

EDWIN L. RELLER.
